UNITED STATES PATENT OFFICE.

ARTHUR W. McCORD, OF WASHINGTON, DISTRICT OF COLUMBIA.

RAPID-ADJUSTABLE WRENCH.

1,204,999.

Specification of Letters Patent. Patented Nov. 14, 1916.

Application filed April 11, 1916. Serial No. 90,404.

To all whom it may concern:

Be it known that I, ARTHUR W. McCORD, a citizen of the United States, residing at Washington, in the District of Columbia, have invented new and useful Improvements in Rapid-Adjustable Wrenches, of which the following is a specification.

This invention relates to improvements in tools and more particularly to rapid adjustable wrenches.

It is the object of this invention to provide a wrench with a rapid and fine adjustment, the rapid adjustment being automatic and the fine adjustment being manually operated, in which the movement of the same element performs both adjustments.

It is the further object of this invention to so construct the device for engaging the adjustment element that it will positively engage and secure the element upon the rapid adjustment irrespective of the relation of the position of the element to the wrench proper. The advantages of this construction are many, among which are that the rapid adjustment is automatic and is controlled by the same hand that grasps the wrench without removing the hand from the handle, whereby various sized nuts may be engaged or released by the automatic adjustment. Another advantage is that upon actuating the rapid adjustment the adjustment element will always be positively locked in that exact position by the engaging device.

A further advantage is that, if an automatic rapid adjustment is closer or looser than required, the exact adjustment desired may be obtained by manually operating the adjustment element without releasing it from the engaging device, and this fine adjustment may be made by the same hand that grasps the handle. As the rapid and fine adjustment may be made by the same hand that holds the wrench, it is of particular advantage where the position of the nut to be operated is such that it can be reached by one hand only, as sometimes occurs on large engines and automobiles.

While the preferred form of this invention is illustrated upon the accompanying sheet of drawing yet it is to be understood that minor detail changes may be made without departing from the scope thereof.

Figure 1 is a view in side elevation of this improved wrench. Fig. 2 is a longitudinal central sectional view of Fig. 1. Fig. 3 is

a transverse sectional view through the engaging device on the line 3—3 of Fig. 2. Fig. 4 is an enlarged longitudinal central sectional view taken on the line 4—4 of Fig. 3. 60

This improved wrench comprises a fixed jaw 1 having a shank 2 extending through the handle 3. A movable jaw 4 is mounted to engage and slide on the shank between the fixed jaw and handle and is preferably provided with a lip 5 extending slightly beyond the end of the fixed jaw. The handle 3 extends from the shank 2 on the side of the projecting jaws 1 and 4 and may be formed integral with the shank, if desired. The 70 handle and adjacent portion of the movable jaw are provided with coaxial bores 6 and 7 parallel with the shank, in which is mounted a screw-threaded rod or adjustment element 8. The portion of the adjustment element 75 entering the movable jaw is not threaded and is rotatably held in engagement with the jaw by a knurled ring 9 secured thereto, as by a pin 10, and held intermediate the length of the bore in rotative engagement 80 between the walls 11 of a cut-out portion of the body of the jaw. The bore 7 in the handle is slightly greater in diameter than the screw-threaded adjustment element 7 and the lower end of the adjustment element is 85 provided with an enlarged guiding head 12 slidably engaging the bore whereby the screw-threaded adjustment element is centered parallel to the shank between the movable jaw and the handle and the screw- 90 threaded portion held out of contact with the handle bore. A coil spring 13 is inserted in the handle bore to engage the guide head on the adjustment element and the outer end of the bore closed, preferably by a screw- 95 threaded cap 14. The spring will normally tend to hold the movable jaw against the fixed jaw and will return the movable jaw toward the fixed jaw when the movable jaw is moved away therefrom and released. 100

To maintain the movable jaw in fixed position upon the shank the outer wall of the handle bore adjacent the upper end of the handle is cut away and the sides of the handle and shank are recessed to receive an engaging device in the form of a half-nut 15 correspondingly threaded to the threaded portion of the adjustment element having sides 16 extending through recesses in the sides of the handle and shank which sides are connected exteriorly of the shank by a strap forming a push button 17. The threads 110

of the half-nut portion are normally held in engagement with the threads of the adjustment element by a spring 18 preferably between the exterior of the shank and the push button. This engaging device will not only maintain the adjustment element against the tension of the spring but will allow of adjustment of the movable jaw independent of the spring by the threaded engagement 5 allowed of a manual operation of the adjustment element through the turning of the knurled ring.

The pressure upon the engaging device is taken up by the walls 19 of the cut-out portion and the walls 20 of the recesses in the handle and shank. To provide for the complete engagement of the threads of the half-nut with the adjustment element the side walls 20 of the recesses in the side of 10 the handle and shank receiving the extending sides of the half-nut are tapered slightly toward the exterior of the shank whereby a slight play is provided for the extending sides to transmit an angular movement to 15 the half-nut so that should the points of the threads of the half-nut fail to fall directly between the points of the threads of the adjustment element, upon a spring operated rapid adjustment, the play of the sides will 20 produce sufficient angular movement to the points of the threads upon the half-nut to cause them to enter into full engagement 25 with the threads upon the adjustment element.

If desired, the handle may be provided 30 with a set-in grip 21, partially of wood, or, if desired, may be provided with a complete grip of wood or other material, or may be of metal integral with the shank. The portion 35 of the handle containing the bore may be integral with the shank, as shown, or may be constructed separately and secured to the shank, without departing from the scope of 40 this invention.

What I claim is:—

1. In a rapid adjustable wrench, a fixed jaw, a shank thereon, a movable jaw slidable upon the shank, a handle, a spring-

pressed screw-threaded adjustment element 50 slidably mounted in the handle and rotatably engaging the movable jaw, threaded means upon the upper end of the handle for detachably engaging the threads of the adjustment element for performing a rapid adjustment, and means for rotating the adjustment element for manually performing a fine adjustment of the movable jaw.

2. In a rapid adjustable wrench, a fixed jaw, a shank thereon, a movable jaw slidable 55 upon the shank, a handle, said movable jaw and handle provided with coaxial bores and having cut-out portions entering into said respective bores, a screw-threaded adjustment element mounted in said bores having a rotatable engagement with a movable jaw 60 and a rotatable and slidable engagement with the handle, a spring in the handle bore between the ends of the said element and handle, a manually operable ring secured to the adjustment element in the cut-out 65 portion of the movable jaw, and a spring-pressed releasable half-nut normally in engagement with the threads of the adjustment element slidably mounted in the recess in the handle.

3. In a rapid adjustable wrench, a fixed jaw, a shank thereon, a movable jaw slidably mounted upon the shank, a handle having a bore parallel with the shank and having a cut-out portion entering into said bore, 80 a spring-pressed screw-threaded adjustment element mounted in the bore in engagement with the movable jaw, a spring-pressed releasable threaded half-nut normally engaging the threads of the adjustment element 85 mounted in the cut-out portion of the handle, and means providing an angular movement of said half-nut whereby the threads of the nut will angularly adjust themselves to completely engage the threads of the adjustment element.

ARTHUR W. McCORD.
